UNITED STATES PATENT OFFICE.

WILLIAM R. FOX, OF GRAND RAPIDS, MICHIGAN.

RIBBON MECHANISM FOR TYPE-WRITERS.

No. 854,207.

Specification of Letters Patent.

Patented May 21, 1907.

Application filed October 28, 1904. Serial No. 230,680.

To all whom it may concern:

Be it known that I, WILLIAM R. FOX, a citizen of the United States, residing at the city of Grand Rapids, county of Kent, State of Michigan, have invented certain new and useful Improvements in Ribbon Mechanism for Type-Writers, of which the following is a specification.

This invention relates to improvements in the ribbon mechanism for use with multi-colored ribbons on typewriters.

The objects of this invention are to provide a simple and convenient means for adjusting the ribbon so that different portions of the same may be used for the purpose of printing different colors, or the printing with different portions may be to secure printing from different qualities of ribbon as with copying ribbon or a non-copying, or record ribbon; also to provide a mechanism that will utilize the full width of ribbon of a single color or quality; and also to provide a multi-colored ribbon mechanism which can be controlled by the hand of the operator from the keyboard when it is desired to readily shift the same from one color to the other in the progress of typewriting.

Further objects, and objects pertaining to details of construction, will definitely appear from the detailed description to follow.

I accomplish the objects of my invention by the devices and means described in the following specification.

The invention is clearly defined and pointed out in the claims.

A structure embodying the features of my invention is clearly illustrated in the accompanying drawing forming a part of this specification, in which—

Figure 1 is a detail side elevation view of a typewriter embodying the features of my improved multi-color mechanism, portions of the frame being broken away and other parts being shown in section. Fig. 2 is a front elevation view of the upper portion of the machine appearing in Fig. 1, the carriage and escapement mechanism being removed. Fig. 3 is a transverse detail sectional view taken on line 3—3 of Fig. 2, showing the connections for shifting the ribbon when it is desired to change from one color to the other in the progress of the printing. Fig. 4 is a rear elevation view of substantially the same parts appearing in Fig. 2. Fig. 5 is an enlarged detail sectional view on line 5—5 of Fig. 4, looking toward the left, the connect-

ing mechanism being thrown out of connection. Fig. 6 is a detail rear elevation view of the parts appearing in Fig. 5. Fig. 7 is a sectional view on line 5—5 of Fig. 4, locking 60 toward the right, showing the notched collar for the connection. Fig. 8 is an enlarged detail rear side elevation view of the parts appearing in Fig. 7.

In the drawing, the sectional views are 65 taken looking in the direction of the little arrows at the ends of the section lines, and similar letters of reference refer to similar parts throughout the several views.

The mechanism for shifting the ribbon 70 back and forth laterally while it is being fed through the machine is the same as that appearing and described in the patent application of myself and Glenn J. Barrett, Serial No. 117,775, filed July 31, 1902. That particular mechanism is not claimed specifically here, but only so much and such parts of the same as relate to the multi-colored ribbon feature.

The particular features which I seek to 80 patent here could be made use of in connection with other shifting mechanism than that I have here shown.

The ribbon spools C' are mounted on sleeves which are mounted on the shafts C. 85 The ribbon spools C' are adapted to reciprocate and also to be adjusted laterally thereon, being held to rotate with such shafts by suitable means. An arm X is on the shaft C and a pin x is carried by the end of the arm X and 90 is arranged parallel with the shaft C and extends into the body of the spool so that the spool can reciprocate thereon. This causes the spool and shaft to revolve together.

Each spool is engaged by a pitman D'' 95 which is connected to an arm D' on the rock shaft D opposite each spool. The rock shaft D is caused to oscillate by means of the slotted lever E embracing a wrist pin on the disk F''. The disk F'' is actuated by the ratchet 100 wheel F', to which it is secured, the same being supported on a suitable journal F. A ratchet pawl f is pivoted to the spacer bar G and held yieldingly in contact with the ratchet wheel by means of a coiled spring f''. 105 A detent f' engages the wheel F'.

The arm D' is secured to the end of the rock shaft D. The arm E is secured to a collar E' which is on the shaft D and is free to oscillate thereon. The collar E' is provided, 110 on its end, with projecting teeth g, diametrically opposite each other.

- The collar *d* is on the shaft *D* and is adjustable back and forth thereon. This collar is held against rotation by a pin *i* extending into a longitudinal slot *i'* in the collar *d*.
 5 A peripheral groove *H'* is cut in this collar *d*. A spring catch *H* with a curved engaging portion *h* is secured to the collar *E'* and is of such length that it engages in the peripheral groove *H'*.
 10 Across the face of the collar *d* are slots *i''*. These slots are to receive the teeth *g* on the face of the collar *E'*, the collar *d* being adjustable back and forth, so that it may entirely disengage the teeth *g*, or the teeth *g* may rest in the slot *i'* or in either of the slots *i''*. When the teeth rest in the slots *i''* they fit the same very closely and shift the spool so that the full width of the ribbon is utilized, in which position, it is of course in position
 15 20 for use with a plain ribbon.

When a multi-colored ribbon is inserted, the collar *d* is withdrawn and adjusted, so that the teeth will engage either in the right-hand or left-hand slot *i''*, which slots are
 25 made of such width that there is lost motion, and either color of the ribbon may be utilized. The full width of the ribbon can be utilized when a ribbon of uniform color is substituted. Then, when it is desired to shift the
 30 ribbon for writing a word at a time of red, while the main writing is black, the collar *d* is withdrawn entirely from engagement with the collar *E'* and the ribbon is shifted back and forth at will by pushing one or the other
 35 of the push buttons and connections *e* or *e'* which are connected to a cross-arm *E''* on the shaft *D*.

Thus, it will be seen that, by a very simple device, it is possible to adjust this machine to
 40 print a full width of ribbon of the ordinary kind, or shift it permanently from one side to the other to use either a red and black, or other party-colored ribbon, or a ribbon which is one-half copy and one-half record; or, by
 45 disconnecting the automatic shift, the ribbon can be moved from the red to the black, or vice versa, by a mere pushing of the proper buttons, so that a single word or number, or more, can be printed in red where the bulk or
 50 body of the work is being printed in black, or vice versa.

Having thus described my invention, what I claim as new and desire to secure by Letters Patent is—

- 55 1. In a ribbon mechanism for typewriters, the combination of ribbon spools supported on suitable sleeves; shafts on which said sleeves are adjustably mounted and adapted to reciprocate thereon; connections from the
 60 shaft to the spool whereby the same will be rotated together; driving mechanism for the spool shafts; a transverse rock shaft *D* to the rear of the machine; upwardly-extending arms *D'* secured to said rock shaft *D* and link connections therefrom to suitable col-

lars on said sleeves; a collar *E'* on said rock shaft *D* provided with teeth *g* on its face; a spring on the periphery of the collar *E'* having an inwardly deflecting engaging portion *h*; a collar *d* mounted on said rock shaft, having a longitudinal slot *i'* therein and lateral notches *i''* to receive the teeth *g*, said notches *i''* being larger than the teeth so that there is lost motion between them, also having a peripheral groove *H'* arranged to receive the engaging portion *h* of the spring *H*; a pin *i* extending through the shaft *D* and engaging the slot *i'* in said collar *d*; a downwardly extending arm or lever *E* to secure said collar *E'* containing a longitudinal slot; a disk bearing wrist pin arranged to engage said slot to actuate said arm; a ratchet wheel connected to said disk and a pawl connected to the spacer mechanism for actuating said ratchet wheel to cause the lever and collar *E'* to oscillate; and a cross-arm *E''* on the rock shaft *D*, having connections *e* and *e'* connecting with push buttons at the front of the machine, all co-acting substantially as described and for the purpose specified.

2. In a ribbon mechanism for typewriters, the combination of ribbon spools supported on suitable sleeves; shafts on which said sleeves are adjustably mounted and adapted to reciprocate thereon; connections from the shaft to the spool whereby the same will be rotated together; driving mechanism for the spool shafts; a transverse rock shaft *D* to the rear of the machine; upwardly-extending arms *D'* secured to said rock shaft *D* and link connections therefrom to suitable collars on said sleeves; a collar *E'* on said rock shaft *D* provided with teeth *g* on its face; a spring on the periphery of the collar *E'* having an inwardly deflecting engaging portion *h*; a collar *d* mounted on said rock shaft, having a longitudinal slot *i'* therein and lateral notches *i''* to receive the teeth *g*, said notches *i''* being larger than the teeth so that there is lost motion between them, also having a peripheral groove *H'* arranged to receive the engaging portion *h* of the spring *H*; a pin *i* extending through the shaft *D* and engaging the slot *i'* in said collar *d*; a downwardly extending arm or lever *E* to secure said collar *E'*, containing a longitudinal slot; a disk bearing a wrist pin arranged to engage said slot to actuate said arm; a ratchet wheel connected to said disk and a pawl connected to the spacer mechanism for actuating said ratchet wheel to cause the lever and collar *E'* to oscillate, all co-acting for the purpose specified.

3. In a ribbon mechanism for typewriters, the combination of ribbon spools supported on suitable sleeves; shafts on which said sleeves are adjustably mounted and adapted to reciprocate thereon; connections from the shaft to the spool whereby the same will be rotated together; driving mechanism for the spool shafts; a transverse rock shaft *D* to the rear of the machine; upwardly-extending arms *D'* secured to said rock shaft *D* and link connections therefrom to suitable col-

rear of the machine; upwardly extending arms D' secured to said rock shaft D and link connections therefrom to suitable collars on said sleeves; a collar E' on said rock shaft D provided with teeth g on its face; a spring on the periphery of the collar E' having an inwardly deflecting engaging portion h; a collar d mounted on said rock shaft, having a longitudinal slot i' therein and lateral notches i'' to receive the teeth g, said notches i'' being larger than the teeth so that there is lost motion between them, also having a peripheral groove H' arranged to receive the engaging portion h of the spring H; a pin i extending through the shaft D and engaging the slot i' in said collar d; a downwardly extending arm or lever E to secure said collar E', containing a longitudinal slot; a disk bearing a wrist pin arranged to engage said slot to actuate said arm; and a ratchet wheel connected to said disk and a pawl connected to the spacer mechanism for actuating said ratchet wheel to cause the lever and collar E' to oscillate, all co-acting substantially as described and for the purpose specified.

15 5. In a ribbon mechanism for typewriters, the combination with laterally adjustable ribbon spools of a driving mechanism for said spools; a transverse rock shaft D to the rear of the machine; upwardly extending arms D' secured to said rock shaft D and link connec-

20 tions therefrom to the spool supports; a collar E' on said rock shaft D provided with teeth g on its face; a spring on the periphery of the collar E' having an inwardly deflecting 25 engaging portion h; a collar d mounted on said rock shaft, having a longitudinal slot i' therein and lateral notches i'' to receive the teeth g, said notches i'' being larger than the teeth so that there is lost motion between 30 them, also having a peripheral groove H' arranged to receive the engaging portion h of the spring H; a pin i extending through the shaft D and engaging the slot i' in said collar d; a downwardly extending arm or lever E to 35 secure said collar E', containing a longitudinal slot; a disk bearing a wrist pin arranged to engage said slot to actuate said arm; a ratchet wheel connected to said disk and a pawl connected to the spacer mechanism for 40 actuating said ratchet wheel to cause the lever and collar E' to oscillate; and a cross-arm E'' on the rock shaft D, having connections e and e' connecting with push buttons at the front of the machine, all co-acting sub- 45 stantially as described and for the purpose specified.

50 5. In a ribbon mechanism for typewriters, the combination with laterally adjustable ribbon spools of a driving mechanism for said spools; a transverse rock shaft D to the rear of the machine; upwardly extending arms D' secured to said rock shaft D and link connec- 55 tions therefrom to the spool supports; a collar E' on said rock shaft D provided with teeth g on its face; a spring on the periphery of the collar E' having an inwardly deflecting 60 engaging portion h; a collar d mounted on said rock shaft, having a longitudinal slot i' therein and lateral notches i'' to receive the teeth g, said notches i'' being larger than the

teeth so that there is lost motion between them, also having a peripheral groove H' arranged to receive the engaging portion h of the spring H; a pin i extending through the shaft D and engaging the slot i' in said collar d; a downwardly extending arm or lever E to secure said collar E', containing a longitudinal slot; a disk bearing a wrist pin arranged to engage said slot to actuate said arm; and a ratchet wheel connected to said disk and a pawl connected to the spacer mechanism for actuating said ratchet wheel to cause the lever and collar E' to oscillate, all co-acting substantially as described and for the purpose specified.

70 6. In a ribbon mechanism for typewriters, the combination with the ribbon spools laterally adjustable of a driving mechanism for said spools; a transverse rock shaft D to the rear of the machine; upwardly extending arms D' secured to said rock shaft D and link connec- 75 tions therefrom to the spool supports; a collar E' on said rock shaft D provided with teeth g on its face; a spring on the periphery of the collar E' having an inwardly deflecting 80 engaging portion h; a collar d mounted on said rock shaft, having a longitudinal slot i' therein and lateral notches i'' to receive the teeth g, said notches being larger than the teeth so that there is lost motion between them, also having a peripheral groove H' arranged to receive the engaging portion h of the spring H; a pin i extending through the shaft D and engaging the slot i' in the said collar d; and means connected to 85 said typewriter for controlling the rock shaft D, for the purpose specified.

90 7. In a ribbon mechanism for typewriters, the combination with the ribbon spools laterally adjustable, of a driving mechanism therefor; means for shifting the spools laterally; a rock shaft to which said means is connected; a collar on the rock shaft connected to the actuating means, having a suitable tooth, and a longitudinally adjustable 95 collar on the rock shaft coupled to rock therewith, containing suitable notches to receive the tooth of the opposing collar, certain of said notches being enlarged to permit of lost motion to oscillate the ribbon through 100 105 only a part of its width; and a spring clamping means for retaining said collars together, for the purpose specified.

110 8. In a ribbon mechanism for typewriters, the combination with the ribbon spools laterally adjustable of a driving mechanism therefor; means for shifting the spools laterally; a rock shaft to which said means is connected; a collar on the rock shaft connected to the actuating means, having a suitable tooth, and a longitudinally adjustable 115 collar on the rock shaft coupled to rock therewith, containing suitable notches to receive the tooth of the opposing collar, certain of said notches being enlarged to permit of lost 120 125 motion to oscillate the ribbon through only a part of its width; and a spring clamping means for retaining said collars together, for the purpose specified.

130

motion to oscillate the ribbon through only a part of its width, co-acting for the purpose specified.

9. In a ribbon mechanism for typewriters, the combination of ribbon spools that are laterally movable; a driving mechanism therefor; a rock shaft with connections thereto for shifting the ribbon spools; a shifting mechanism for actuating said rock shaft; clutch members on said rock shaft with an adjustable connection between them, whereby the ribbon mechanism can be set to oscillate its full width or a portion of its width at either side, for the purpose specified.

10. In a ribbon mechanism for typewriters, the combination of laterally movable ribbon spools; a mechanism for oscillating the said spools, connected to a movable part of the machine; and a clutch between said mechanism and the movable part of the machine, the members of which are adapted to be adjustably connected together or entirely disconnected, for the purpose specified.

11. In a ribbon mechanism for typewriters, the combination of laterally movable ribbon

spools; a mechanism for oscillating the said spools, connected to a movable part of the machine; a clutch between said mechanism and a movable part of the machine, the members of which are adapted to be adjustably connected together; and a key for shifting said ribbon spools when the clutch is disconnected, for the purpose specified.

12. In a ribbon mechanism for typewriters, the combination of laterally movable ribbon spools; a mechanism for oscillating the said spools, connected to a movable part of the machine; a clutch between said mechanism and a movable part of the machine; and a key for shifting the ribbon spools when the clutch is disconnected, for the purpose specified.

In witness whereof, I have hereunto set my hand and seal in the presence of two witnesses.

WILLIAM R. FOX. [L.S.]
